US00D807870S

(12) **United States Design Patent** (10) **Patent No.:** **US D807,870 S**
(45) **Date of Patent:** **** Jan. 16, 2018**

(54) **COVER FOR AN ELECTRONIC DEVICE**

(71) Applicant: **SAMSUNG ELECTRONICS CO., LTD.**, Suwon-si (KR)

(72) Inventors: **Wooseok Lee**, Seoul (KR); **Junyong Song**, Seongnam-si (KR)

(73) Assignee: **Samsung Electronics Co., Ltd.**, Suwon-si (KR)

(**) Term: **15 Years**

(21) Appl. No.: **29/568,892**

(22) Filed: **Jun. 22, 2016**

(30) **Foreign Application Priority Data**

Dec. 24, 2015 (KR) 30-2015-0066082

(51) **LOC (11) Cl.** **14-03**

(52) **U.S. Cl.**

USPC **D14/250**

(58) **Field of Classification Search**

USPC D14/250; 455/575.8

CPC A45C 11/00; A45C 2011/002

(57) **CLAIM**

We claim the ornamental design for a cover for an electronic device, as shown and described.

DESCRIPTION

FIG. 1 is a front perspective view of a cover for an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a right-side view of the cover for an electronic device in which a camera lens is provided in broken lines to illustrate an example environment; and,

FIG. 10 is a rear perspective view of the cover for an electronic device in which a camera lens is provided in broken lines to illustrate an example environment.

The broken lines in the figures depict environmental subject matter and form no part of the claimed design.

1 Claim, 8 Drawing Sheets
